UNITED STATES PATENT OFFICE.

SUMNER A. DUDLEY, OF HOPEDALE, MASSACHUSETTS, ASSIGNOR TO THE AMERICAN SPINDLE COMPANY, OF SACO, MAINE.

LOOM-SHUTTLE.

SPECIFICATION forming part of Letters Patent No. 394,963, dated December 25, 1888.

Application filed July 23, 1887. Serial No. 245,066. (No model.)

To all whom it may concern:

Be it known that I, SUMNER A. DUDLEY, of Hopedale, in the county of Worcester, State of Massachusetts, have invented a certain 5 new and useful Improvement in Loom-Shuttles, of which the following is a description sufficiently full, clear, and exact to enable any person skilled in the art or science to which said invention appertains to make and 10 use the same, reference being had to the accompanying drawings, forming part of this specification, in which—

Figure 1 is a sectional view of a loom-shuttle, showing the bobbin on the spindle and 15 the spindle depressed or in position for use, a portion of the shuttle-body, bobbin, and spindle being represented as broken off; Fig 2, a side elevation of the spindle detached, the head of the spindle being shown in vertical 20 section; and Fig. 3, a bottom plan view of the spindle detached.

Like letters of reference indicate corresponding parts in the different figures of the drawings.

25 My invention relates to means for locking the bobbin to the spindle; and it consists in a novel construction and arrangement of parts, as hereinafter more fully set forth and claimed, the object being to produce a simpler, cheaper, and more effective device of 30 this character than is now in ordinary use.

The nature and operation of the improvement will be readily understood by all conversant with such matters from the following 35 explanation.

In the drawings, A represents the body of the shuttle; B, the spindle, and C the bobbin. The body is mortised longitudinally to receive the spindle and bobbin, and is otherwise of the 40 ordinary form and construction, excepting as hereinafter set forth. The head *f* of the spindle is provided with a socket, *x*, from the bottom of which a hole, *t*, extends vertically through said head for the reception of a push-pin, *m*, which is fitted to work freely therein. A horizontally-arranged finger, *l*, is secured to the lower end of the pin *m* beneath the head *f*, said finger being curved in cross-section at 45 its forward or free end to correspond with the contour of the head of the bobbin C, as shown

at *z*. The pin *m* is provided with a head, *d*, and disposed in the socket *x*, around the body of said pin, there is a coiled spring, *y*, the lower end of which rests on the bottom of said socket and the upper end against said 55 head, said spring acting expansively to draw the rear end of the finger *l* upward toward the bottom of the head *f* and cause its forward or free end to press forcibly on the head of the bobbin. The rear end of the finger *l* is secured to a block, *v*, through which the lower end of the pin *m* also passes, and beneath 60 which it is headed, as shown at *i*. The lower side of the head *f* is cut out or rabbeted to receive the block *v* and form a bearing or shoulder, *k*, against which the rear end of said block presses when there is a strain on the finger *l*, thus bracing or staying the pin *m* and preventing it from wearing away its bearings 65 in the hole *t* as rapidly as it otherwise would. 70

The bobbin C is provided with the usual hole through its center for the reception of the spindle B, and also with an interiorly-disposed annular groove, *r*; for the reception of a flange, *g*, which is formed on the body of the 75 spindle B near the head *f*. The spindle is pivoted in the body of the shuttle in the usual manner on a pin, *h*, which passes transversely through a hole, *w*, in the spindle-head *f*.

Any of the ordinary means adapted to this 80 improved shuttle may be employed for holding the spindle in closed or open position. The means shown comprise a headed movable pin, *4*, in a longitudinal socket, *2*, in the body of the shuttle, and a spiral spring, *3*, interposed between the bottom of said socket and the head of the pin, said spring acting expansively to press the head of the pin *4* against the head *f* of the spindle, whereby the spindle is held in closed or open position in 85 the ordinary manner.

A projection or stop, *j*, is formed or disposed on the interior of the body A, against which the head *d* of the pin *m* strikes when the spindle is elevated to "doff" the shuttle. 95

In the use of my improvement, the shuttle being empty the spindle is raised, as shown by the dotted lines in Fig. 1, thereby bringing the head *d* of the pin *m* into contact with the projection *j*, compressing the spring *y*, and 100

forcing the finger *l* away from the spindle *B* a sufficient distance to permit the head of the bobbin to pass between the outer end of said finger and the outer end of the flange *g*. The 5 bobbin *C* is then placed on the spindle and the spindle depressed, and as the head *d* of the pin *m* is withdrawn from the projection *j* the expansive action of the spring *y* causes the end of the finger *l* to press on the head of 10 the bobbin and the flange *g* to enter the groove *r*, thereby locking the bobbin on the spindle in a manner which will be readily obvious without a more explicit description.

I do not confine myself to the use of the 15 block *r* and shoulder *k*, as these may be omitted, if desired; neither do I confine myself to laterally curving the outer end of the finger *l*, as shown at *z*, as this feature may also be omitted; nor to constructing the stop *j* 20 integral with the body *A*, as a screw inserted in said body, at or near that point against which the pin *m* may strike, will serve the same purpose; nor to constructing the stop in the form shown, as the body may be otherwise 25 wise so formed as to constitute a stop against which the pin *m* will strike as the spindle is elevated and thereby compress the spring *y*.

Having thus explained my invention, what I claim is—
30 1. The combination of a shuttle-body, a spindle pivoted therein and provided with a head and with a flange near its head for engaging the bobbin, said head having a socket

and hole extending therethrough, a pin movable in said hole and socket, a finger on said pin, and a spring within said socket around said pin for actuating the pin to cause the finger to press on the bobbin. 35

2. The combination of a shuttle-body, a spindle pivoted therein and provided with a head and with a flange near its head for engaging the bobbin, said head having a socket and hole extending therethrough, a pin movable in said hole and socket, a finger on said pin, a spring within said socket around said 40 pin for actuating the pin to cause the finger to press on the bobbin, and a stop on said body with which said pin comes in contact to release said finger when the spindle is elevated. 45

3. The combination of a shuttle-body, a spindle pivoted therein and provided with a head and with a flange near its head for engaging the bobbin, said head having a socket and hole extending therethrough, a pin movable in said hole and socket, a finger on said pin, and a spring within said socket around said pin for actuating the pin to cause the finger to press on the bobbin, said head having a shoulder on its under side against which the shank of said finger rests when the finger 50 presses on the bobbin. 55

SUMNER A. DUDLEY.
